BABY BIB

Phyllis A. Turner, Dover, Del., assignor to International Latex Corporation, Dover, Del., a corporation of Delaware

Application September 25, 1956, Serial No. 43,075

Term of patent 14 years

(Cl. D3—26)

The drawing is a front elevational view of a baby bib incorporating my design.

The dominant feature of the design resides in the overall appearance of a baby bib having a front piece of rough textured fabric and shoulder pieces of translucent plastic film shaped as shown.

I claim:

The ornamental design for a baby bib, as shown and described.
